Attorney

UNITED STATES PATENT OFFICE.

JAMES GILMORE, OF DE WITT, IOWA.

FIRE-WOOD-SAWING MACHINE.

SPECIFICATION forming part of Letters Patent No. 333,848, dated January 5, 1886.

Application filed October 13, 1885. Serial No. 179,758. (No model.)

To all whom it may concern:

Be it known that I, JAMES GILMORE, a citizen of the United States, residing at De Witt, in the county of Clinton and State of Iowa, have invented certain new and useful Improvements in Fire-Wood-Sawing Machines; and I do hereby declare the following to be a full, clear, and exact description of the invention, such as will enable others skilled in the art to which it appertains to make and use the same.

My invention relates to fire-wood-sawing machines; and it has for its object to produce a light, yet strong, substantial, and durable machine which can be worked by hand, foot, or steam power, though I have illustrated it for operation by hand-power alone; and it consists in the parts and combinations of parts hereinafter described and claimed.

20 In the drawings forming a part of this specification, Figure 1 is a perspective view of my machine, and Fig. 2 is a side elevation of the same.

Similar letters refer to similar parts throughout the several views.

The supporting-frame is made of iron, and is composed of two horizontal beams, A, two legs, A', at one end, joined together by a cross-piece, B, and brace-bars B'. The other end of the frame 30 is supported by an adjustable frame, C, which is pivoted to the beams A, and which carries a handle, c, by which it may be adjusted at a more or less acute angle to the beams A, and thus raise or lower the forward or saw end of the frame to accommodate logs of a greater or less diameter. To the upper side of the beams A are secured two uprights, D, which are braced apart by a rod, d, and which support the saw-carrying frame by means of the bar e, acting 35 as a pivot, passing through the horizontal frame E and said uprights. The bars composing the frame E are joined at their lever end by a bar, and at their other end carry the upright or swinging frame F by means of the 40 rod f, which is passed through the bars of the swinging frame, and through the ends of the bars forming the horizontal frame E, the ends of said bars being cut out, so as to clamp the bars of the upright frame F, to permit the 45 swinging movement of said frame. To the lower end of the swinging frame is secured, by

means of clamping-plates g, the saws G, the clamping-plates being pivoted to said frame. Suitable holes are provided in the bars for the reception of the pins or pivots i of the 55 saws, so that the latter may be adjusted along the bars to accommodate logs of varying size. To the ends of the beams A, I secure the saw-guide H, which is provided with slots h, for the saws G to run in. I also form a slot in the 60 brace-bar I. Pins or retaining-wedges K pass through the ends of the beams A and into the log which is being operated upon, so as to hold it steady and prevent rolling. I connect to the center bar of the swinging frame F the 65 end of a pitman, L, said pitman extending back, and being connected, by means of a removable wrist-pin, l, to a double split crank, M, said crank being provided with 70 perforations, so that the throw of the pitman 75 may be lengthened or shortened by moving it along said crank. To one of the shafts N is secured a pinion, O, which meshes with a gear-wheel, P, said gear-wheel being carried by a short shaft journaled to one of the beams A, 75 while the other shaft N carries a fly-wheel, R. I show a crank-handle, S, for revolving the short shaft that carries the gear-wheel P; but it may be operated by a belt and pulley or by 80 a treadle.

Projecting upward from one side of one of the beams A is a bar or upright, T, having a series of perforations, and from the horizontal frame E extends a lever, U, said lever having a handle formed on its end, and being provided with a perforation at a short distance from said handle, through which may pass a pin, u. By means of pin u and the perforations in the lever U and upright T, I am enabled to raise or lower the entire frame by simply raising or lowering the lever, and thus always 85 keep the saws working level.

If desired, the frame B, being pivoted to the beams A, may be moved to the position shown in broken lines in Fig. 2, and thus lower that 95 end of the frame of the machine. I may use as many saws as I desire by inserting bars in the swinging frame to support the same. (See bar in dotted lines, Fig. 1.)

Having thus described my invention, what 100 I claim as new, and desire to secure by Letters Patent, is—

1. In a fire-wood-sawing machine, the combination of the main frame, a pivoted support for one end thereof, the upright D, the horizontal frame and lever U, pivoted thereto, the 5 perforated upright T, secured to the main frame, the adjusting-pin u, securing the lever to said upright, the swinging frame F, carrying the saws, the saw-guide H, and suitable operating mechanism, substantially as and for the purpose described.

2. In a fire-wood-sawing machine, the combination of the main frame, an adjustable pivoted support therefor, the perforated upright T, the upright D, the horizontal frame E, pivotally secured to said uprights, the perforated lever U, secured to the frame E and adjustably secured to the upright T, the swinging frame F, pivotally secured to frame E, the saws G, adjustably and pivotally secured to frame F, the 20 saw-guide H, a pitman, and means for driving the same, all as and for the purpose set forth.

3. A fire-wood-sawing machine comprising the following instrumentalities: a main frame, an adjustable support therefor, a slotted brace-bar, a slotted saw-guide, retaining-pins, a 25 perforated upright, T, a lever, U, a horizontal frame, E, pivoted to uprights D, a swinging frame, saws adjustably pivoted to the lower end of said swinging frame, a pitman pivotally secured to one of the bars of said 30 frame, a double split crank to which the pitman is adjustably secured, the shafts N, pinion O, secured to one of said shafts, and fly-wheel R to the other, the gear-wheel P, and crank-handle S, all as and for the purpose set 35 forth.

In testimony whereof I affix my signature in presence of two witnesses.

JAMES GILMORE.
